Attorney

UNITED STATES PATENT OFFICE.

JOHN F. BURKE, OF PHILADELPHIA, PENNSYLVANIA.

COASTER-DIVING APPARATUS.

1,230,559.

Specification of Letters Patent. Patented June 19, 1917.

Application filed November 4, 1916. Serial No. 129,424.

To all whom it may concern:

Be it known that I, JOHN F. BURKE, a citizen of the United States, and resident of Philadelphia, county of Philadelphia and State of Pennsylvania, have invented an Improvement in Coaster-Diving Apparatus, of which the following is a specification.

This invention relates to the class of devices used at bathing resorts and amusement parks to furnish healthful recreation to men, women and children.

The object of my invention is to supply safe means whereby men, women or children may obtain pleasure by coasting down an inclined railway in a suitable car, receive a pleasant shower bath of water, *en route*, followed by a dive through the air into water or other safe landing place.

More specifically considering the invention, I provide an inclined railway terminating abruptly, a car, traversing the same, equipped with suitable means for engaging a buffer located at the lower termination of the inclined railway, and means beneath the lower termination of the railway for safely receiving passengers projected or involuntarily diving from the car. My invention further consists in providing, an automatic switch at the lower termination of the railway whereby the car, impelled by the compressed spring action of the buffer is returned over a second or return track to a starting platform, and thence raised to the starting point at the top of the inclined railway by a suitable hoisting mechanism. Likewise, there is desirably located near the lower termination of the railway means arranged to spray water on the car and its occupants as it passes beneath the same and before they are catapulted into the water.

My invention further consists of features of construction which are fully set out hereinafter and more particularly defined in the claims.

For the purpose of illustrating my invention, I have shown in the accompanying drawings the form thereof which is at present preferred by me, since the same is in form to give satisfactory and reliable results, but it is to be understood that the several instrumentalities, of which my invention consists, can be variously arranged and organized and that my invention is not limited

to the precise arrangement and organization of these instrumentalities as herein shown and described.

Referring to the drawings:—Figure 1 represents an elevation of the inclined railway embodying my invention; Fig. 2 is a plan view of the car and lower portion of the track; and Fig. 3 is an elevation of the car.

I provide an inclined or gravity railway track A of any desirable incline, with or without undulations, the construction of which may follow ordinary commercial practice, having two rails and suitable means (not shown) to prevent the car from jumping the track. This track at its terminal part ends abruptly and is suitably provided with a strong spring buffer C to receive the impact of the cars. Beyond the end of the track is an expanse of water D such as a river or ocean front; and as it is desirable that this water shall be reasonably deep, I prefer to provide a suitable net D' to receive the occupants of the car when projected therefrom into the water. The terminal end of the track is provided with a return track F and automatic switch E, preferably spring actuated for returning the cars to a position for receiving another load of passengers. As shown, the return track F inclines backward and downward to a receiving platform G, so that the returning empty cars are automatically returned by gravity after being started on the return trip under the impelling action of the buffer C. From the receiving platform G, the cars with their passengers are pulled up the incline track H by cable H' to the highest point I in the gravity railway A and from where the loaded cars are started on their journey. The details of this track construction and cable will need no further description, as they will follow ordinary well known constructive practice.

The car B is of simple construction and built with as low a center of gravity as possible. Along the length of its platform B' are arranged two upright guide boards J, J, 100 preferably curved outward or apart at their forward ends J'. Each side of the platform of the car toward the rear is also provided with an upright board K. This construction provides three longitudinal spaces in 105 which the passengers may lie in prostrate

position, the one in the middle space with head forward, and those in the side spaces with feet forward.

The rear of the platform is provided with 5 a transverse upright board L abutting the longitudinal boards J and K, and is provided with padded portions M against which the passengers may rest. Furthermore, the upper edges of the longitudinal boards J and 10 K near the middle of the length of the car may be provided with handles N projecting in a forward direction so that the passenger may hold himself against the action of inertia when the car is speeding down the 15 railway, but which will permit the hands to slip off forward when the passengers are projected from the car when it collides with the buffer C.

The under portion of the car body is provided with a downwardly extending buffer contact O which may be of metal or wood; and said contact is so positioned that at the termination of the journey it abruptly strikes the spring buffer C and brings the 20 car to an abrupt stop, though not too violently. The stop should be with sufficient force to project or catapult the persons from the car platform into the water.

The platform and longitudinal boards J, 25 K, should be very smooth and finished so that the persons may freely slide over their surfaces without undue friction or danger from splinters.

The water body D may be natural or artificial, as found desirable or necessary, and where water is not available, the net D' may be relied upon as the receiving means of the projected passengers.

The passengers may mount the car at 40 platform G and be elevated to the top of the railway at I where the car is switched on to the main track A.

In use, the passengers, attired in bathing suits, extend themselves in prostrate positions between the boards J, K, on the car. The use of the head or foot rest L M on the car is now apparent. If they so desire, the occupants may grasp the hood grips or handles N, which are so shaped that when the 45 car is suddenly stopped they cannot retain their hold of the same and thus cause themselves injury. When ready, the car is started by an attendant on its downward path. It gains increasing velocity and 50 when the end of the track is reached, the buffer engaging part O on the car engages the buffer C, putting its springs under compression. Thus the car is brought to a stop so suddenly that the occupants are projected 55 through the air into the water beneath. The raised guide boards J, K, serve to guide the body of the center occupant along the line of travel of the car, but the outer occupants are guided away from the center line of the 60 car and thus the danger of collision be- 65

tween the bathers in the air or in the water is eliminated.

The car, relieved of its load, is impelled in reverse direction by the springs of the buffer C, and passes over the switch E on to 70 the return track F, and reaches the starting platform G where it is ready for another load.

As a further feature of my invention, I prefer to provide means along the railway 75 A for spraying the occupants of the car with water before they are projected into the water, and this may be accomplished by suitable spraying devices P, shown by way of example as spray pipes arranged along 80 the track and preferably near the terminus thereof, so that the occupants of the car will be well soaked before being projected into the water. The particular means for spraying the car and passengers is not material, and any suitable means for imparting a preliminary wetting may be employed.

While the passengers may lie prostrate on the car platform with their heads or feet foremost as desired, I have arranged it preferably for the center passenger to lie with the head foremost while the side passengers may lie with feet foremost, but this arrangement is optional with the occupants of the car. Furthermore, while the car is shown as adapted for three passengers, it is to be understood that I do not limit myself in this respect, as it may be arranged for 90 any number desired.

It will now be apparent that I have devised a novel and useful construction which embodies the features of advantage enumerated as desirable in the statement of the invention and the above description, and while I have in the present instance shown and described the preferred embodiment thereof which is best suited to give satisfactory and reliable results in practice, it is to be understood that the same is susceptible of modification in various particulars without departing from the spirit or scope of the invention or sacrificing any of its advantages.

Having now described my invention, what I claim as new and desire to secure by Letters Patent, is:—

1. A gravity railway having an abrupt termination at its lower end, combined with a car capable of traversing said railway, means adjacent the termination of the railway for bringing the car while in full motion to a sudden stop to project its passengers into the air, means for returning the car to the upper end of the railway, and means immediately beyond the end of the railway for yieldingly receiving the projected passengers.

2. A gravity railway having an abrupt termination at its lower end, combined with a car capable of traversing said railway, means adjacent the termination of the rail- 130

- way for bringing the car while in full motion to a sudden stop to project its passengers into the air, means for returning the car to the upper end of the railway, and 5 means immediately beyond the end of the railway for yieldingly receiving the projected passengers comprising a body of water and a net arranged in the water. 3. A gravity railway having an abrupt 10 termination at its lower end, combined with a car capable of traversing said railway, means adjacent the termination of the railway for bringing the car while in full motion to a sudden stop to project its passengers into the air, means for returning the car to the upper end of the railway, and a body of water immediately beyond the end 15 of the railway for yieldingly receiving the projected passengers. 4. A gravity railway having an abrupt 20 termination at its lower end, combined with a car capable of traversing said railway, means adjacent the termination of the railway for bringing the car while in full motion to a sudden stop to project its passengers into the air, means for returning the car to the upper end of the railway, and a stretched net immediately beyond the end 25 of the railway for yieldingly receiving the projected passengers. 5. A gravity railway having an abrupt 30 termination at its lower end, combined with a car capable of traversing said railway, means adjacent the termination of the railway for bringing the car while in full motion to a sudden stop to project its passengers into the air, means for returning the car to the upper end of the railway, and a body of water arranged for said railway, and means for arresting the rapid travel of the car close to the termination of the railway to project the passengers from the car into 35 the body of water. 6. A gravity railway having an abrupt 40 termination at its lower end, combined with a car capable of traversing said railway, means adjacent the termination of the railway for bringing the car while in full motion to a sudden stop to project its passengers into the air, means for spraying the car and its occupants with water before reaching the terminus of the railway, and 45 means for returning the car to the upper end of the railway. 7. A gravity railway having an abrupt 50 termination at its lower end, combined with a return track and switch from said termination of the gravity railway to receive and 55 return the cars, a car for said railway, a spring buffer device for automatically arresting the travel of the car on the gravity railway and reversing its motion for transferring it on to the return track, and means 60 beyond the end of the termination of the 65 gravity railway to receive the passengers projected from the car. 8. A gravity railway having an abrupt 70 termination at its lower end, combined with a return track and switch from said termination of the gravity railway to receive and return the cars, a car for said railway, a spring buffer device for automatically arresting the travel of the car on the gravity 75 railway and reversing its motion for transferring it on to the return track, a receiving platform at the terminus of the return track, an elevating track and cable for raising the car to the top of the gravity railway, and means beyond the end of the termination of the gravity railway to receive the passengers projected from the car. 9. In an apparatus of the character stated, a gravity railway terminating abruptly over a body of water, combined with a car for 80 passengers arranged for said railway, and means for arresting the rapid travel of the car close to the termination of the railway to project the passengers from the car into the body of water. 10. In an apparatus of the character 85 stated, a gravity railway terminating abruptly over a body of water, combined with a car for passengers arranged for said railway, means for arresting the rapid travel of the car close to the termination of the railway to project the passengers from the car into the body of water, and means to return the car to the top of the gravity railway. 11. In an apparatus of the character 90 stated, a gravity railway terminating abruptly, combined with a car having a smooth floor and guiding longitudinal boards for separating the passengers lying prostrate upon the floor, means for arresting the rapid travel of the car close to the termination of the railway for projecting the passengers from the car into the air, and means to yieldingly receive the passengers arranged beyond the abrupt termination of the railway. 12. In an apparatus of the character 95 stated, a gravity railway terminating abruptly, combined with a car having a smooth floor and guiding longitudinal 100 boards for separating the passengers lying prostrate upon the floor and a transverse board at the rear of the floor and having pads, means for arresting the rapid travel of the car close to the termination of the railway for projecting the passengers from the car into the air, and means to yieldingly receive the passengers arranged beyond the abrupt termination of the railway. 13. In an apparatus of the character 105 stated, a gravity railway terminating abruptly, combined with a car having a smooth floor and guiding longitudinal 110 boards for separating the passengers lying prostrate upon the floor, a transverse up- 115 120 125 130

wardly extending board at the rear of the car, and also handles on the longitudinal guiding boards, means for arresting the rapid travel of the car close to the termination of the railway for projecting the passengers from the car into the air, and means to yieldingly receive the passengers arranged beyond the abrupt termination of the railway.

10 14. In an apparatus of the character stated, a gravity railway terminating abruptly, combined with a car having a smooth floor and guiding longitudinal boards for separating the passengers lying 15 prostrate upon the floor said boards com-

prising two middle boards flaring apart at the forward end and shorter boards at the sides, means for arresting the rapid travel of the car close to the termination of the railway for projecting the passengers from the car into the air, and means to yieldingly receive the passengers arranged beyond the abrupt termination of the railway. 20

In testimony of which invention, I hereunto set my hand.
